UNITED STATES PATENT OFFICE.

BERNARD MULLER-THYM, OF KANSAS CITY, MISSOURI.

SANCTUARY-LAMP.

1,269,732.

Specification of Letters Patent. Patented June 18, 1918.

Application filed November 5, 1917. Serial No. 200,453.

To all whom it may concern:

Be it known that I, BERNARD MULLER-THYM, a citizen of the United States, residing at Kansas City, in the county of Jackson and State of Missouri, have invented certain new and useful Improvements in Sanctuary-Lamps, of which the following is a specification.

This invention relates to sanctuary lamps, and my object is to produce a lamp which will burn for several days with any one of several common but strictly vegetable oils as distinguished from the highly refined rapeseed oil made in France and now impossible to obtain.

Heretofore such common oils have been successfully burned for from twelve to twenty-four hours when used in conjunction with a float-supported wax taper, after which the flame would be extinguished either through the consumption of the wick or the deposit of carbon thereon. It has been unsuccessfully attempted to burn such common strictly vegetable oils by surrounding a wick standing in a vessel charged with the oil, with a floating burner, so that as the oil is consumed, the floating burner shall descend and thus gradually expose a new or uncharred portion of the wick to the flame. This idea has proved fallacious however, as with such oils, a crust or carbon deposit forms on the wick below the flame and prevents the latter spreading downward and therefore in a short time, effects the extinguishment of the flame.

Lamps of the type under consideration are properly for burning strictly vegetable oils only, and I have found that such oils—which will not burn without a taper or wick—produce a crust or deposit on the wick just below the flame, which deposit in a relatively short period causes the extinguishment of the flame, as above stated. With a wick or taper which moves upwardly through the oil, I have overcome this difficulty, as the crust which forms on the wick, passes up through the flame therefrom and does not extinguish the same, but on the contrary is burned off the wick. This elimination of the crust or deposit is desirable in the interest of compactness, as it permits of the use of a short endless wick of asbestos or analogous material for travel over suitable guides and through the oil, or of a wick susceptible of being unwound from a drum submerged in the oil and upon a drum above

the oil, after it has performed its function as a wick.

With the object mentioned in view, the invention consists in certain novel and useful features of construction and combinations of parts as hereinafter described and claimed and in order that it may be fully understood reference is to be had to the accompanying drawing, in which:—

Fig. 1, is a central vertical section of a sanctuary lamp embodying my invention.

Fig. 2, is a top plan view of same.

Fig. 3, is a view partially in elevation and partly in vertical section, of another form of the lamp.

Fig. 4, is a vertical section of the wick or taper and feeding mechanism therefor, of a slightly different type from the corresponding parts of Figs. 1 and 3.

In the said drawing, where like reference characters identify corresponding parts, 1 indicates a vessel of any suitable or preferred type and of capacity to hold enough oil to burn for a predetermined period, eight days for instance.

Arranged within the vessel is a wick stretching member or weight 2 and journaled on said weight is a wheel or drum 3 around which extends a wick 4 of any suitable non-combustible material, such as asbestos or fire-proofed cotton. This wick in all cases extends up through the oil in the vessel and in Figs. 1 and 3 the wick is in the form of an endless cable, and in Fig. 1 the wick extends over and around a grooved sheave 5, journaled on a cross-shaft or rod 6 secured by bearing cap 7 to a ring 8 fitting upon the upper end of the vessel. In Fig. 3 the wick is also an endless wick and at the upper end of the vessel engages a spirally grooved sleeve 9 secured upon the shaft 10 of a clock work (not shown) the clockwork being operated at a predetermined speed found by experience to give the best results in controlling the size of the flame, as it is desirable from an economic standpoint that the flame shall be as small as possible. It will be understood of course that the groove of the sleeve shall be of such length that the wick shall not be materially shifted along the length of the sleeve by the time the wick has traveled a distance equal to its length and therefore exposed its entire surface to the action of the flame. I have found that the speed of travel of the wick should vary according to the character of oil employed,

moving faster for light oils than when used with heavy oils, and I have also found that the use of a wick of this character is practical with common strictly vegetable oils, which is not true of the type of lamp employing a stationary wick and a floating burner, as the latter will burn successfully only with a highly refined French rapeseed oil.

- 10 In Fig. 4 I show a drum 11, mounted upon the clockwork shaft 10, and in this construction the wheel 3 is also in the form of a drum with the wick initially wound thereon and attached at its upper end to drum 11. 15 so that as the latter is turned, the wick will be gradually unwound from drum 3 and wound upon drum 11.

In all cases that portion of the wick that moves upwardly, from the surface of the oil, 20 is ignited. In the initial part of the operation, the flame will be elongated owing to the fact that the wick by capillary attraction is impregnated with oil for a considerable distance above the surface of the body 25 of oil in the vessel, but in a short time the flame is reduced and remains reduced in size during the entire period of service. I have found in all cases that the wick at the point where it emerges from the body of oil, 30 comes coated with a hard crust-like scale but that such scale by the time the wick carries it nearly to the top of the flame is burned off, so that it can form no impediment to the proper travel of the wick over the wheel 35 5 or the spirally grooved sleeve 9, or the drum 11.

I have found, that the lamp operates very successfully in the manner described without the use of any burner, though a burner may 40 be employed if the most economical consumption of oil is desired, and in Fig. 1, I illustrate a burner which is constructed as follows:

12 indicates a float set in the oil and provided with a central tubular portion 13, within which the oil stands and through which the upwardly moving portion of the wick extends, and supported in the tubular portion of the float is a burner cap 14, having a central opening 15 at its top through which the wick extends, and a series of air intake inlet holes 16 through which air may enter and be heated to make the oil within

the tubular portion sufficiently limpid to freely ascend the taper or wick to the burning point thereof.

From the foregoing it will be apparent that I have produced a lamp possessing the features of advantage enumerated as desirable in the statement of the object of the invention, and while I have illustrated and described the preferred embodiments of the invention, it will be understood that I reserve the right to all changes of form, proportion, detail construction and arrangement of parts that properly fall within the spirit and scope of the appended claims.

I claim:

1. A sanctuary lamp, comprising a vessel, a wick extending through oil in the vessel, and means for suspending the wick from a point above the highest range of the flame therefrom. 70

2. A sanctuary lamp, comprising a vessel, a wick extending through oil in the vessel, means for suspending the wick from a point above the highest range of the flame therefrom, and means for holding the wick in stretched condition. 75

3. A sanctuary lamp, comprising a vessel, a wick extending through oil in the vessel, means for suspending the wick from a point above the highest range of the flame therefrom, and automatic means for imparting upward travel to the wick. 80 85

4. A sanctuary lamp, comprising a vessel, a wick extending through oil in the vessel, means for suspending the wick from a point above the highest range of the flame therefrom, means for holding the wick in stretched condition, and means for imparting upward travel to the wick. 90

5. A sanctuary lamp, comprising a vessel, a support above the level of oil contained by the vessel, a weight within the vessel, a wick extending through the oil in the vessel and connected to the said support and weight and held taut by the latter, and means to operate the support to effect the feed of the wick upward from the weight to and upon the said support. 95 100

In testimony whereof, I hereunto affix my signature this 26th day of October, 1917, at Kansas City, Jackson county, Missouri.

BERNARD MULLER-THYM.
